UNITED STATES PATENT OFFICE.

JOSEPH KAUFMAN, OF BRONXVILLE, NEW YORK, ASSIGNOR TO AMERICAN SAFETY RAZOR CORPORATION, OF NEW YORK, N. Y., A CORPORATION OF VIRGINIA.

DESIGN FOR A RAZOR CONTAINER.

Application filed January 29, 1925. Serial No. 12,182. Term of patent 14 years.

To all whom it may concern:

Be it known that I, JOSEPH KAUFMAN, a citizen of the United States, and a resident of Bronxville, county of Westchester, and State of New York, have invented a new, original, and ornamental Design for a Razor Container, of which the following is a specification, reference being had to the accompanying drawing forming part of this specification.

Fig. 1 is a perspective view of my razor container; and

Fig. 2 is a similar view showing the container open—the safety razor and the blade being shown in dotted lines.

I claim:

The ornamental design for a razor container as shown.

In witness whereof, I have hereunder signed my name this 27th day of January, 1925.

JOSEPH KAUFMAN.
